UNITED STATES PATENT OFFICE.

CLAUDE L. POST, OF CHICAGO, ILLINOIS.

PRINTING-PLATE-CLAMPING MEANS.

Original application filed December 6, 1920, Serial No. 428,691. Divided and this application filed September 8, 1921. Serial No. 499,158.

To all whom it may concern:

Be it known that I, CLAUDE L. POST, a citizen of the United States, residing at Chicago, in the county of Cook and State of Illinois, have invented certain new and useful Improvements in Printing-Plate-Clamping Means, of which the following is a description.

My invention relates to improvements in plate clamping means, and more particularly to means adapted to removably position a printing plate upon a type roll or the like, and is a divisional application of Serial No. 428,691, filed December 6, 1920, for an envelope handling device.

One of the objects of my invention is to provide a plate clamping means which permits of the plate being adjusted longitudinally and circumferentially of the roll, the entire plate clamping device being removable from the roll, for the purpose of cleaning, adjusting, renewing, etc.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view of the printing roll showing a type plate held in place thereon;

Fig. 2 is a detail of the platen roll and type carrying roll;

Fig. 3 is a section taken substantially on the line 3—3 of Fig. 2;

Fig. 4 is a section taken substantially on the line 4—4 of Fig. 1;

Fig. 5 is a view similar to that shown in Fig. 1, showing a different size printing plate in position;

Fig. 6 is a section taken substantially on the line 6—6 of Fig. 5, and

Fig. 7 is a section taken substantially on the line 7—7 of Fig. 1.

In the drawings, wherein I have illustrated a preferred embodiment of my invention, there is shown a feed or impression roll 1, co-operating with a type or printing roll 2, the feed roll having a tympan 3 removably secured thereon, and also having a

feeding arc 4 adapted to cooperate with a feeding arc 5 secured on the type roll as shown in Figs. 2 and 3, the envelopes or other matter to be printed being delivered between the rolls 1 and 2 in any suitable manner. Auxiliary feeding rings 17 encircle the roll 2 and are removably secured thereon in any suitable manner.

The type roll 2 is intended to receive a printing plate 6 to be used in the printing operation of the sheets fed through the rolls, the printing plate preferably being curved in cross section to seat on the roll 2 and being beveled at its edges as at 7.

Extending longitudinally of the type roll 2 are one or more circumferentially spaced grooves or slots 8, said grooves being preferably wedge-shaped or dovetailed in radial cross section. Type holding clamping members 9, also wedge-shaped in cross section so as to be slidable in the dovetailed slots 8, are positioned in the slots and are movable radially therein so as to become wedged in place when moved outwardly. The members 9 are bored and threaded at 10, 10', longitudinally of said slots, the threading on the right and lefthand members of the pair of clamps being reverse, that is, one of the members 9 has a righthand thread 10 therethrough and the other has a lefthand thread 10'. The portions of the clamps projecting outwardly of the grooves are each recessed or shouldered as at 11, the shoulders overhanging the bottom of the recesses and being beveled to cooperatively engage with the bevels or chamfers on the edges of the plate 6.

Extending longitudinally within the dovetailed slot 8 and insertable thereinto from one end of the roll is a threaded bar 12, having a knob or gripping portion 13 preferably detachably secured at its outer end, whereby the bar may be manually adjusted, the body of the bar being divided into two oppositely threaded portions 14 and 15, one of said portions having righthanded threads thereon, and the other of said portions having lefthanded threads thereon, so that each of said portions may receive its respectively threaded clamping member 9.

Thus it is seen that a rotation of the threaded bar 12 will move clamping elements 9 in unison toward one another so as to clamp or release the type or printing plate held therebetween. It is to be further

noted that inasmuch as both the clamps and the printing plate have cooperating beveled edges, the clamping movement will move or slide the plate downwardly of the clamps, 5 due to the cooperating tapers and force the plate downwardly on the type roll and will also force the clamps radially outwardly of the dovetailed slots, thereby wedging the clamps in place in the slots and firmly fixing 10 their position longitudinally as well as radially of the type roll. By this method it is not necessary that both ends of the operating rod 12 be journaled in the slot, because when the rod is free to move radially of the 15 slot, as has been previously described, the type will be clamped in position on the roll and held against radial and longitudinal movement thereon.

The centering of the printing plate is 20 automatic to accommodate different length plates, as shown in Figs. 4 and 5, in which the plate 6' is longer than 6, but the centering may be adjustably varied by the rotation of the clamping elements individually 25 on the bar after the bar and clamps have been removed entirely free of the slots, whereupon after such adjustment the assembly bar and clamping plates may be re-inserted into the slots.

30 Having thus described my invention, it is obvious that various immaterial modifications may be made in the same without departing from the spirit of my invention; hence I do not wish to be understood as 35 limiting myself to the exact form, construction, arrangement and combination of parts herein shown and described or uses mentioned.

What I claim as new and desire to secure 40 by Letters Patent is:

1. In a printing press, a type roll having a longitudinal slot therein, a threaded rod insertable within said slot from one end of said roll and movable radially of said slot, and spaced type clamping members threadedly engageable with said rod and movable longitudinally thereby to receive and clamp a printing plate therebetween.

2. In a printing press, a type roll having 50 a longitudinal slot therein, and means for adjustably positioning a type plate along said roll, said type-holding means comprising a screw-threaded member radially movable in said slot and having righthand and lefthand threaded portions, and clamping members longitudinally slidable in said slot and carried on said oppositely threaded screw threaded member, the operation of said screw-threaded member moving said 55 clamping members in unison in relatively opposite directions.

3. In a printing press, a type roll having 60 a slot therein, spaced type-holding clamping members movable longitudinally in said slot and each having a threaded aperture there-

through, a rod insertable in said slot so as to be radially movable therein and having righthand and lefthand threaded portions engageable with said type-holding clamping members to move them in unison relatively 70 to one another, said type-holding clamping members being individually adjustable on said rod so that the midpoint between said clamping members may be adjusted longitudinally of the roll.

4. In a printing press, a type roll having a longitudinal slot therein, clamping members longitudinally slidable in said slot and having beveled shoulders extending outwardly of said slot and adapted to receive a printing plate thereat, said clamping members each having a relatively reversely threaded aperture therethrough, a rod insertable in said slot longitudinally thereof from one end of the roll so as to be longitudinally slidable thereon and having oppositely threaded portions thereon engageable with the reversely threaded clamping members, whereby the actuation of said rod will move said clamping members in unison to 90 clamp said type plate therebetween.

5. In a printing press, a type roll having a longitudinal slot opening on the periphery thereof, said slot being tapered in radial cross-section, a rod insertable longitudinally 95 of said slot and radially movable therein, a pair of clamps carried by said rod and being slidable longitudinally in said slot and projecting therebeyond, said clamps being tapered in radial cross-section, and interengaging means between said rod and clamps for moving said clamps toward or from each other in unison in said slot.

6. In a printing press, a type roll having a wedge-shaped longitudinal slot opening onto the periphery thereof, a rod removably insertable into said slot longitudinally thereof from one end of said roll and radially movable in said slot, a pair of wedge-shaped clamps slidable in said slot and carried by 105 said rod, said clamps having beveled shoulders adapted to receive a cooperatively beveled printing plate therebetween, and means for moving said clamps in unison on said rod to wedge said clamps in said slot, 110 and move said printing plate towards said roll.

7. In a printing press, a type roll having a wedge-shaped slot longitudinally thereof, a pair of spaced clamps wedge-shaped in 120 cross-section and radially slidable in said slot, and having a portion extending outwardly therebeyond, said outwardly-extending portion having beveled shoulders, a type plate adapted to be received on said roll between said beveled shoulders, one of said clamps having a righthanded threaded aperture therethrough and the other of said clamps having a lefthanded threaded aperture therethrough, a rod insertable into said 125 slot.

slot from one end of the roll and radially slidable therein, said rod having right and lefthanded threaded portions thereon so as to threadedly engage the respective righthand and lefthand threaded clamping members, whereby the operation of said rod will move said clamps toward one another to clamp the printing plate therebetween and move it radially inwardly toward the type 10 roll.

8. In a printing press, a type roll having a wedge-shaped slot longitudinally thereof, a pair of clamps slidable in said slot and wedge-shaped in cross-section and having a portion extending outwardly beyond said slot, said outwardly-extending portion having beveled shoulders, a type plate adapted to be received on said roll between said beveled shoulders, one of said clamps having a righthanded threaded aperture therethrough and the other of said clamps having a lefthanded threaded aperture therethrough, a rod longitudinally insertable into said slot from one end of the roll and movable 25 radially of said slot, said rod having adjacent right and lefthanded threaded portions thereon to threadedly engage the respective righthand and lefthand threaded clamping members, whereby the operating 30 of said rod will move said clamps toward one another to clamp the printing plate therebetween and move it radially inwardly toward the type roll and also wedge the clamps in the groove to lock them in place 35 against longitudinal movement.

9. In a printing press, a type roll having a dovetailed slot longitudinally thereof and opening onto the periphery, a rod removably

inserted into the slot from one end of said roll and movable longitudinally and radially therein, said rod having adjacent right and lefthanded threaded portions, a type clamp threadedly engageable with and carried on each of said threaded portions of the rod, said clamps being dovetailed in 45 cross-section so as to be movable longitudinally and radially in said slot and extending outwardly therebeyond, the outwardly-extending portions of said clamps having beveled shoulders thereat adapted to receive 50 a beveled-edge printing plate therebetween, whereby the rotation of said rod will move said clamps toward each other to removably clamp said plate therebetween, the cooperating beveled edges of said plate and the 55 beveled shoulders of said clamps drawing said plate down toward the roll and moving said clamps outwardly to wedge them in said slot.

10. In a printing press, a type roll having a longitudinal slot therein, a threaded rod insertable within said slot from one end of said roll and movable radially of said slot, and spaced type clamping members threadedly engageable with said rod and movable 65 radially and longitudinally thereby to receive and clamp a printing plate therebetween against accidental radial or lengthwise movement.

In testimony whereof, I have hereunto 70 signed my name in the presence of two subscribing witnesses.
